Attorney

UNITED STATES PATENT OFFICE

JACOB B. SEGAL, OF CAMDEN, NEW JERSEY

EMBROIDERY FRAME

Application filed April 19, 1932. Serial No. 606,193.

This invention relates to a frame especially designed for embroidery work and more particularly to an embroidery frame for rugs, carpets and the like, although not necessarily limited to such.

In accordance with the present invention a knockdown frame is provided having improved means for securing the uprights and feet in assembled relation, and also having improved means for securing the end members of the work frame at the desired angular adjustment upon the uprights.

The invention together with its numerous objects and advantages will be best understood from a study of the following description, taken in connection with the accompanying drawings wherein:

Figure 1 is an end elevational view, the work frame being shown at an angle to the perpendicular.

Figure 2 is a side elevational view of the embroidery frame.

Figure 3 is a perspective view showing a foot, an upright, a spreader bar, together with an end and two side members of the work frame separated.

Figures 4 and 6 are sectional views taken substantially on the lines 4-4 and 6-6 respectively of Figure 1, and

Figure 5 is a perspective view of a U-shaped cap.

Figure 7 is a perspective view of a hook equipped plate for the work frame.

Referring more in detail to the drawings it will be seen that the frame, in the proposed form thereof, comprises a pair of supporting feet 10 each having an intermediate portion notched on relatively opposite sides as at 11 to thereby reduce the intermediate portion thereof; the intermediate reduced portion of the foot being provided with a pair of vertically spaced apertures 12.

A pair of uprights 13 are each provided at the lower ends thereof with slots 14 receiving the reduced intermediate portions of the feet 10 and vertically spaced apertures 15 on relatively opposite sides of the slot to align with the apertures 12.

A spreader bar 16 is provided and the

same at each end thereof is equipped with a pair of relatively spaced threaded pins 17 adapted to pass through coinciding apertures 12 and 15, wing nuts 18 being threaded on the end of the pins 17 for securing the uprights 13 in assembled relation with the feet 10.

The upper ends of the uprights 13 are each provided with vertical longitudinal slots 19 and coinciding notches 20 at relatively opposite sides of the slot.

A working frame comprises end members 21 and longitudinal members or runners 22 of square cross section and each having threaded pins 23 at the ends thereof extending through apertures in the members 21, wing nuts 24 being threaded on the ends of the pins 23 for securing the end members 21 and longitudinal members 22 assembled.

The end members 21 intermediate their ends are notched on relatively opposite sides as at 25 the notches being elongated longitudinally as shown in Figure 3, thereby providing relatively elongated reduced portions having apertures 26.

A substantially U-shaped cap 27 of spring metal straddles the intermediate portion of each frame member 21 and has its sides 27a laterally engaging the upper end of a proximate upright and having its apertures 28 aligning with the aperture 26 and receiving a bolt 30 with which is engaged a wing nut 29; the wing nut when tightened urging the sides of the cap into frictional engagement with the upright and thereby securing the working frame at the desired angular adjustment.

As is well known the burlap or other material on which the embroidery or design is to be worked is ordinarily rolled upon one of the longitudinal members 22, and the material stretched between the members 22. It is also common practice to use a cord, thread or the like for connecting the free edges of the material with the end members of the frame, and to this end, there is provided, in accordance with the present invention a plurality of channel shaped plates 31 preferably formed of metal, each plate having one side 31a thereof at its free longi-

tudinal edge provided with an inwardly directed longitudinal flange 32 while the relatively opposite side 31b of the plate is provided on its outer face with a longitudinal series of relatively spaced flat hooks 33 similar to hooks provided on the upper of a shoe of the type known as a lace shoe. In actual practice, and as shown in the drawings preferably two of such plates 31 are provided on each frame member 21, it being seen that the plates 31 are arranged adjacent the ends of the members 21, the members 21 being received in the channel of the plate with the flanges 32 of the plate engaging the inner side of the frame member as shown in Figure 6. In use the referred to cord or thread is engaged with the edges of the material stretched between the longitudinal members 22 of the frame, and the hooks 33, in a manner well known in the art.

Even though I have herein shown and described the preferred embodiment of the invention, it is to be understood that the same is susceptible of further changes, modifications and improvements coming within the scope of the appended claims.

Having thus described my invention, what I claim as new is:

1. In an embroidery frame of the knock-down type, a supporting structure comprising a pair of uprights each having a slot at one end, and apertures at relatively opposite sides of the slot, a pair of feet each having a laterally reduced apertured intermediate portion arranged in the slot of an upright, a spreader member having threaded pins on the ends thereof adapted to pass through the apertures in the uprights and feet and be secured by wing nuts to maintain the uprights and feet in assembled relation, and a working frame pivotally mounted on the supporting structure.

2. In an embroidery frame, a pair of uprights each having a slot at one end and aligned notches at the outer end of the slot, a pair of end frame members each having a reduced apertured intermediate portion arranged in the slot of an upright, and a U cap straddling the reduced portion of the frame member and having sides paralleling the end of the upright; a bolt extending through said sides of the cap and engaging said notches, and a hand nut engaging the bolt to urge the sides of the cap into frictional engagement with the upright and securing the frame member at the desired angle; and longitudinal frame members connecting the end frame members.

3. An embroidery frame including in combination an upright, a frame member, a cap straddling an intermediate portion of said frame member, and having sides adapted to receive therebetween the upper end portion of said upright, a bolt adapted to rest on the upper end of said upright, and extending

through said sides of the cap, and a nut threadedly engaged with the bolt for drawing said sides of the cap into frictional engagement with said upright.

In testimony whereof I affix by signature. ⁷⁰
JACOB B. SEGAL.
